[57] **CLAIM**

The ornamental design for a microphone for use with a communications device, as shown and described.

DESCRIPTION

FIG. 1 is a front, top and right side perspective view of a microphone for use with a communications device, showing my new design;

FIG. 2 is a bottom plan view thereof;

FIG. 3 is a rear elevational view thereof; and,

FIG. 4 is a left side elevational view thereof.

The side opposite being similarly a mirror image.

The broken line showing of microphone cables in FIGS. 1, 2, 3 and 4 is for illustrative purposes only and forms no part of the claimed design.

FIG. 3***FIG. 4***
